SECTIONAL DOOR CONSTRUCTION

Wilfred R. Mitchell, East Detroit, Mich., assignor
to Crawford Door Company, Detroit, Mich., a
corporation of Michigan

Application November 4, 1946, Serial No. 707,639

3 Claims. (Cl. 189—46)

1

This invention relates to a door construction suitable for garage door installations and the like.

Specifically the invention deals with a light-weight metal sectional garage door.

According to this invention, sheet metal, such as aluminum, is rolled into door sections or panels containing stiffening or rigidifying beads and top and bottom flanges. End strips are riveted or otherwise secured to the back faces of the rolled metal sections. These end strips have an offset or recessed portion secured to the back face of the rolled metal section so that the main face or front wall of the strip will project into flush relationship with the outer extremities of the beads thereby closing any gaps that would normally occur because of these rolled bead portions. The end strips present a flat end face to have sealing engagement with weatherstrips carried on the door jambs. So-called "hat" section beams or channels with outturned flanges are riveted or otherwise secured at spaced intervals across the back or inner face of the door sections to further rigidify the sections.

In the multi-sectional garage doors of this invention the rolled door sections are made in convenient panel heights and are hinged together by means of leaf hinges that are riveted or otherwise secured to the hat beams or channels. The top and bottom edges of the rolled sections preferably have offset portions to mesh with each other and form a weatherstrip when the sections are disposed in aligned vertical relationship. The end strips for such sections have roller studs secured therein and rollers on these studs support the door from trackways.

A feature of the invention resides in the utilization of simple rolled sheet metal parts and inexpensive end strips to provide a rigid self-sustaining door assembly.

Another feature of the invention is the provision of rigidifying end strips for sheet metal door sections that have projections such as beads thereon whereby the strips cover the open ends of the beads and present flat faces for sealing engagement with weatherstrips or the like.

An object of the invention is to provide a light-weight rigid metal door suitable for garage doors and the like.

A further object of the invention is to provide an all-metal sectional door construction built up of rolled aluminum or other metal sheets, end strips, and reinforcing channels.

A still further object of the invention is to provide a sectional garage door construction where-

2

in end strips carry roller supports, rigidify the door sections, and close up gaps that would otherwise occur between the door sections and the doorway.

5 Other and further features and objects of the invention will be apparent to those skilled in the art from the following detailed description of the annexed sheets of drawings which, by way of a preferred example only, illustrate one embodiment of the invention.

10 As shown on the drawings:

Figure 1 is an inside elevational view of a sectional garage door according to this invention.

15 Figure 2 is an outside elevational view of one of the door sections of the door shown in Figure 1.

20 Figure 3 is a vertical cross-sectional view, taken along the line III—III of Figure 1 and also showing in dotted lines a tilted position of a door section.

Figure 4 is a horizontal cross-sectional view taken along the line IV—IV of Figure 1.

25 Figure 5 is a horizontal cross-sectional view taken along the line V—V of Figure 1, and with a stud portion in section.

Figure 6 is a vertical cross-sectional view taken along the line VI—VI of Figure 1.

30 Figure 7 is an end elevational view of one of the rolled metal sheets for a door section according to this invention.

35 As shown on the drawings:

In Figure 1, the reference numeral 10 designates a sectional garage door of the upward acting type composed of four substantially identical sections 11. As is known, such sectional garage doors are guided by rollers on trackways from a closed vertical doorway closing position to an overhead horizontal open position.

40 Each door section 11 is composed of a rolled or otherwise formed metal sheet 12, end channels 13, 13, and rigidifying or stiffening "hat" section beams or channels 14 at spaced intervals along the inner face of the metal sheet. Three vertical beams or channels 14 are shown. Rivets 45 connect the strips and beams or channels to the sheet metal, but it should be understood that other forms of fasteners, including welded bonds, could be used.

Leaf hinges 15 connect the adjoining sections 50 11 in articulate relationship, and roller axles 16 carried by the end channels or strips 13 project laterally outwardly therefrom for receiving rollers which ride in the tracks to support the door.

55 As best shown in Figure 7, the rolled sheet

metal panel 12 has a pair of adjacent beads 12a formed therein longitudinally across the middle portion thereof. These beads 12a are conveniently formed by rollers acting on a flat metal sheet such as, for example, an aluminum sheet. The panel 12 has a top bead 12b rolled therein along the upper portion thereof. A bottom bead 12c is also rolled into the sheet along the bottom portion thereof. These top and bottom or outer beads 12b and 12c are conveniently rolled into the metal sheet after the center beads have been formed. A recess R₁ is then rolled in the sheet in spaced relation outwardly from the top bead 12b. A second recess R₂ is then rolled in the sheet immediately adjacent the bottom bead 12c. Flanges are then turned up at the top and bottom ends of the sheet, and these flanged ends are next bent back to provide top and bottom walls. The finished panel thus has stepped top and bottom walls with inturned end flanges. The top wall has a portion 12d extending rearwardly from the bead 12b to an inclined shoulder 12e which slopes upwardly and backwardly to a horizontal end wall portion 12f at a higher level than the portion 12d. A flange 12g extends downwardly at right angles to the wall portion 12f. The recess R₁ provides the shoulder 12e and the wall portion 12f at a raised level relative to the wall portion 12d.

The bottom wall has a horizontal wall portion 12h extending rearwardly from the bead 12c to an upwardly and rearwardly inclined shoulder 12i which extends to a horizontal wall 12j at a level above the wall 12h. A flange 12k extends vertically upward from the inner end of the wall 12j in alignment with the flange 12g.

The panel 12 thus has adjacent parallel beads extending longitudinally across the mid-portion thereof together with longitudinal beads along the top and bottom ends thereof. These beads project outwardly from the outer face of the panel. The panel has stepped horizontal end walls with inturned vertical end flanges. The stepped portions of the end walls are complementary so that two adjacent panels can have their end walls in full seating engagement as best shown in Figure 3.

As best shown in Figures 5 and 6, the end strips 13 for the panel 12 have back flanges or walls 13a overlying the inner faces of the panel flanges 12g and 12k and secured thereto by means of rivets 17. These back walls 13a extend laterally outward from the outer edges of the panels 12 and have flat side faces or walls 13b parallel to the outer edges of the panel in spaced outward relation therefrom, as best shown in Figure 5. The side walls 13b extend forwardly from the back walls 13a beyond the front face of the panels 12 to a front face or wall 13c that is flush with the outer extremities of the beads 12a, 12b, and 12c. These front faces 13c extend inwardly from the side walls 13b to flanges 13d which snugly fit against the ends of the beads and extend rearwardly behind the panel face to walls 13e which underlap the back faces of the panels and are riveted to the panels by means of rivets 18. In order to further stiffen the assembly, these walls 13e have inturned flanges 13f thereon.

The end strips 13 are thus riveted to the outer faces of the panel flanges 12g and 12j and to the inside face of the main portion of the panel sheet. These strips extend outwardly from the outer edges or sides of the panel to present solid end walls 13b and flat front faces 13c flush with the outer extremities of the beads 12c. These front

faces 13c are adapted to sealingly abut weather-strips carried by the door jambs of the doorway in which the door operates (not shown).

As shown in Figure 6, the ends of the strips 13, such as the illustrated top end, terminate at a level intermediate the levels of the panel top walls 12d and 12f so that the strips can have flat ends which are brought into abutting engagement when adjacent panels have their respective top and bottom walls in interfitting relationship, as shown in Figure 3. This arrangement avoids the necessity for trimming the end strips 13 into flush relationship with the stepped top and bottom walls of the panel. Identical end strips can thus be used for all of the panels.

The roller axles 16 are carried in the upper ends of the strips 13 and, as shown in Figures 5 and 6, project through the strips and through a reinforcing plate 19 riveted to the inner face of the strip wall 13b by means of a rivet such as 29. The axle 16 has a shoulder 16a bottomed on the outer face of the strip wall 13b together with a reduced-diameter portion 16b extending through this outer wall and through the plate 19. The reduced-diameter portion is then spread or riveted-peened as at 16c to provide a head for locking the axle in position.

The "hat" section beams or channels 14 are provided to reinforce the panels 12, and are spaced at intervals across the length of the panels. These channels 14, as shown in Figures 1 and 2, include a center channel at the transverse center of each panel, and another channel between the center channel and each end of the panel. All of the channels are vertical or transverse to the longitudinal axis of the panel. Each channel includes, as best shown in Figure 4, a web portion 14a, side walls 14b, 14b, and outturned flanges 14c, 14c. The side walls 14b have sufficient width to position the web 14a into flush mating engagement inside of the panel flanges 12g and 12k when the channel flanges 14c are bottomed on the panel. Thus, as shown in Figures 1 and 4, the channel web 14a fits inside of the panel flanges 12g and 12k. The channel flanges 14c are bottomed on the inner face of the panel 12 and are secured thereto by means of rivets 21. As shown in Figure 3, the ends of the channels terminate substantially flush with the panel walls 12d and 12j.

The hinges 15 are secured to the panel flanges 12g and 12k and to the channel web 14a. Thus, a hinge 15 includes a leaf 15a, best shown in Figures 3 and 4, overlying the panel flange 12k in alignment with a channel web 14a and riveted to both the flange and channel by means of rivets 22. The hinge includes a mating leaf 15b overlying the flange 12g in alignment with the web 14a of the adjacent channel 14 and riveted thereto by means of similar rivets 22. The leaves 15a and 15b are connected by means of a pintle 15c. As shown in Figure 1, a hinge 15 is provided between each aligned channel 14 so that each door section is joined with its adjacent section by means of three hinges.

From the above descriptions it will be clear that this invention now provides rigid, lightweight door constructions especially useful for upward acting sectional-type garage doors.

It will, of course, be understood that various details of construction may be varied through a wide range without departing from the principles of this invention and it is, therefore, not the purpose to limit the patent granted hereon

otherwise than necessitated by the scope of the appended claims.

I claim as my invention:

1. A door construction comprising a sheet metal panel having outturned stiffening beads along the top and bottom ends thereof and intermediate said ends, said panel having rearwardly extending top and bottom walls with inturned end flanges, side strips for said panel having rear flanges overlying said inturned end flanges, side walls spaced outwardly from the side edges of the panel, front walls flush with the outer extremities of the beads, shoulders covering the ends of the beads and flanges overlapping the inner face of the panel, rivets securing the flanges of said strips to the panel and to the panel flanges, and reinforcing beams riveted to the inner face of the panel between said strips. 15

2. A panel for a door construction comprising a rolled sheet metal strip having outturned spaced parallel adjoining beads extending longitudinally thereof intermediate the top and bottom thereof, beads parallel with said first mentioned beads at the top and bottom of the panel, and inwardly extending stepped horizontal walls at the top and bottom of the panel with inturned end flanges, side strips for the panel having stepped front faces including portions flush with the outer extremities of the beads and portions underlying the inner face of the panel together with shoulders connecting the portions for covering the ends of the beads, and means

securing to the panel the portions of the strips underlying the inner face of the panel.

3. A door section comprising a rolled sheet metal panel having top and bottom walls with inturned flanges and a beaded outer face, side strips for the panel having inner flanges secured to the inturned flanges thereof, outer flanges underlying the inner face of the panel, shoulders extending outwardly from the outer flanges to fit snugly against the ends of the beads, and outer faces flush with the outer extremities of the beads to present flat sealing faces.
